PENCIL POINTER

Clifford G. White, Cedar Rapids, Iowa

Application February 24, 1936, Serial No. 65,272

2 Claims. (Cl. 120—96)

This invention relates to pencil pointers and has particular relation to pencil pointers in which the pointing or sharpening mechanism is actuated by power means rather than by manual operation.

Devices of this character made according to the prior art and with which I am familiar have had certain defects. In the first place most of the pencil sharpeners or pointers are operated by hand with several consequent difficulties. In the hand operation of the sharpener the cutter is operated unevenly and at varying speeds. In such cases it is difficult to obtain a properly pointed pencil. In addition the strain imposed on the graphite of the pencil by this uneven operation of the cutter results very often in the breaking of the graphite. Another disadvantage is that the pencil may only be pointed in one manner; that is, with a conical point. When another type of point is desired such as a flat sided or wedge point, often preferred by draftsmen, it is necessary to set such a point by hand. Power-operated sharpeners have had many of the defects of the hand operated sharpeners. In addition they were intricate, expensive and more or less bulky. The latter object making it difficult to move the sharpener around and resulting in the necessity of locating the sharpener permanently.

It is accordingly an object of my invention to provide a simple and comparatively inexpensive power operated pencil pointer of compact and pleasing appearance.

Another object of my invention is to provide a power operated pencil pointer of compact design and light construction so that it may be easily moved about when desired.

A further object of my invention is to provide a pencil pointer which may be used to point pencils in various ways depending on the wishes of the user.

According to my invention I provide a pencil pointer in which the sharpening or cutter mechanism is actuated by a small electric motor. The apparatus is compact and the working parts are closely associated and simple in structure. The device, by reason of its structure, may be easily moved around and it may be used to point pencils in the manner desired by the user.

The novel features which I consider characteristic of my invention are set forth with particularity in the appended claims. The invention itself, however, both as to its organization and its method of operation, together with additional objects and advantages thereof, will best be understood from the following description of a spe-

cific embodiment when read in connection with the accompanying drawing, in which:

Figure 1 is a view in perspective of a pencil pointer constructed in accordance with the principles of my invention.

Figure 2 is a view in perspective showing, in exploded relation, the various parts of a pencil pointer constructed in accordance with the present invention.

Referring now to the drawing, the device shown in Figures 1 and 2 comprises a supporting base 10, a housing 11, having a face plate 12, including a pencil holder or guide 13, a motor or actuating mechanism 14, a base plate 16, and a resilient mounting pad 17.

The base plate 18 is formed of a suitable material to provide a motor support 18 at one portion thereof having a convex surface, as indicated at 19, to conform with the general outline of the small electric motor 14. The other portion 21 of the base 10 serves as a support for the housing 11 and has an opening therethrough to coincide with an opening in the bottom of housing 11, the purpose of which will be hereinafter explained. The base 10 is of hollow construction and the portion 18 supplying the support for the motor is drilled at various points such as indicated at 22 and 23 to provide outlets for a switch 24 and conductor 26 of the motor 14.

The portion 21 of the base extending beneath the housing 11 is so designed that a small drawer 27 may be inserted therein. The drawer 27 serves as a receptacle for retaining shavings and refuse resulting from using the pencil pointer. Obviously it may be withdrawn and the contents discarded when it becomes filled.

The base plate 16 serves as a retainer for the drawer and as a base for mounting the resilient pad 17. The plate 16 is secured to the base 10 in any suitable manner and the resilient pad 17 is secured to the plate 16 by means of cement or some suitable binding agent.

The housing 11 serves to enclose the sharpening device or cutting tool 28. The cutting tool is of the form of a frustum of a cone with the cutting surface finished in the conventional manner of a file and the like. The tool 28 is suitably secured to the armature shaft 29 of the motor 14 so that it rotates with the shaft 29 when the motor is energized.

The rear wall of the housing 11 has an opening (not shown) therethrough to enable the cutting tool 28 to be extended into the housing. The motor 14 is engaged to the rear face by suitable means to hold the cutting tool in fixed position.

within the housing. The front wall of the housing 11 has a boss 31 on the face thereof. A circular aperture 32 extends therethrough to permit extending the pencil holder 13 or guide within the 5 housing as hereinafter explained.

The circular cap or face plate 12 is adapted to be secured to the boss 31 by any suitable means such as stud bolts. The cap is drilled at one portion thereof and the holder or guide 13 is extended therethrough and is securely engaged thereto. The guide 13 consists of a hollow cylindrical member with the portion extending within the housing having one surface of the cylinder cut away as indicated at 33.

15 Of course it is obvious that with the parts in assembled relation the holder 13 and the cutting tool 28 are in proper spaced relation to provide the correct cutting action on a pencil inserted in the device to be sharpened.

20 The housing 11 has an opening (not shown) extending through the lower surface adjacent the base and corresponding with an opening in the base above the drawer 27. Shavings and refuse resulting from pointing a pencil in the device 25 drop through these adjacent openings into the drawer 27 from which they may be discarded.

The pad of resilient material, indicated at 17, serves several purposes. It furnishes a cushioning means so that the device will not mar any 30 finished surface when placed thereon. It serves as a dampener for vibrations and noise resulting from the motor when it is energized and also acts to prevent the pencil pointer from shifting about too easily.

35 The operation of the above described device may be set forth as follows. The motor is energized and a pencil is inserted in the guide or holder 13. If a conical point is desired, the pencil is advanced inwardly and rotated between the fingers. The cutting tool 28, revolving at high 40 speed, contacts the pencil and removes enough material to provide the desired result. If a wedge point is desired, the pencil is held stationary between the fingers and advanced inwardly to the cutter to flatten one side. It is 45 then withdrawn, turned through 180° and the

operation repeated. This procedure will result in a point of the type desired.

It is evident that a pencil pointer constructed in accordance with the principles of my invention has several attendant advantages. It is of 5 simple and inexpensive construction and of compact and pleasing appearance. It does away with the trouble encountered in a hand operated machine such as improper pointing and breaking of the graphite. In addition, my device makes 10 possible the pointing of pencils in various ways to suit the desire of the individual who uses it.

Although I have shown and described a certain specific embodiment of my invention, I am 15 fully aware that many modifications thereof are possible. My invention is therefore not to be restricted except insofar as is necessitated by the prior art and by the spirit of the appended claims.

20 I claim as my invention:

1. In a pencil pointer, a base, a housing mounted on the base, a cutter drive means mounted on the base and secured to the housing on one face thereof, cutting means adapted to be actuated by the cutter drive means and extending within the housing, a cap engaged on the other face of the housing, a pencil holding and guide means secured to the cap and extending therethrough and within the housing in fixed spaced relationship with respect to the cutting means whereby a pencil placed in the holder and moved into the housing will contact the cutting means and have the end formed into a desired point.

2. In a pencil pointer, a base cupped on the upper face thereof, a roughly semi-cylindrical housing extending upwardly from one portion of the base, a cutter drive means received in the cupped face of the base and arranged with the cutter projecting into the housing, a cap mounted on the side of the housing opposite to the cutter driving means, and guide means eccentric to the central axis of the cap projecting through the cap and into juxtaposition to the cutter.

CLIFFORD G. WHITE. 45
